MEANS FOR MEASURING YARNS

Stephen Miller Fulton, Spondon, near Derby, England, assignor to Celanese Corporation of America, a corporation of Delaware

Application October 23, 1934, Serial No. 749,567
In Great Britain November 7, 1933

5 Claims. (Cl. 33—136)

This invention relates to apparatus in which yarns and like materials are unwound from bobbins or like packages, and provides a means of measuring the amount of yarn unwound or of enabling a predetermined amount of yarn to be wound on to another package.

It is often of advantage to be able to measure the amount of yarn being unwound from bobbins and like packages, e. g. cheeses or spools, and also to be able to wind from such packages a predetermined amount of yarn. In the production of weft pirns for weaving, for example, it is of great importance with a view to enabling them to be used on a loom fitted with a weft measuring stop motion, to be able to ensure that each pirn shall contain within small limits the same amount of yarn.

The present invention comprises a measuring apparatus adapted to be used in operations in which yarn is unwound from a bobbin or like package having a substantially constant amount of yarn in each layer, the measuring apparatus being operated by a guide through which the yarn is caused to pass as it leaves the bobbin. The yarn traverses the guide and so drives the measuring apparatus until after a predetermined number of traverses the apparatus causes unwinding to cease. Thus, in a pirn winding machine in which the spindle draws the yarn from the supply bobbin, the measuring apparatus may operate to stop the pirn winder after the yarn has made the desired number of traverses.

Conveniently the traversing guide is mounted on a lever so disposed with respect to the supply bobbin that the guide can move from end to end of the bobbin, and the lever drives by pawl and ratchet mechanism means which after being rotated thereby through a certain distance stop the unwinding of the yarn.

40 The invention will now be described in greater detail with reference to the accompanying drawings, of which

Figs. 1 and 2 are front and side elevations of the measuring device shown mounted on a pirn winding head;

Fig. 3 is a diagrammatic view in perspective of part of the device showing its connection with stop mechanism of the winding head, and

Fig. 4 is a perspective view of the device mounted on the winding head of a standard pirn-winding machine, certain elements of the device being omitted for the sake of clarity.

Referring to Figs. 1 and 2, a parallel wound slow traverse bobbin 10 (e. g. a cap-wound bobbin) is shown carried by supports 11, yarn 12

being led from the package through a slotted guide 13 over a guide 14 and down to the pirn-winding spindle 15 to be traversed in the usual way. The slotted guide 13 is carried by an arm 16 pivoted at 17 so that as the slowly traversed 5 yarn unwinds from the package 10 the guide 13 swings over the length of the package as indicated in dotted lines.

Two pawls 18, 19 carried by the arm 16 above and below the pivot 17 engage a ratchet wheel 10 20 secured to a spindle 21 mounted in a bearing 22 on a supporting bracket 23. A gear 24 on the forward end of the spindle 21 meshes with a gear 25 on a spindle 26 to which is secured a disc 27 having a notch 28 in its periphery with one 15 edge substantially radial and the other edge 29 inclined. A lever 30 pivoted at 31 carries a projection 32 adapted to rest on the periphery of the disc 27. The lever 30 is provided at one end with a weight 33 and at the other end 34 is secured thereto a stiff wire 35 depending downwardly.

As the guide arm 16 rocks to and fro due to the unwinding of the yarn from the bobbin 10, the ratchet wheel 20 is driven in one direction 25 by the pawls 18, 19, the leverage of the arm 16 allowing the slightly tensioned thread to overcome the resistance of the wheel 20 and the mechanism geared to it. The driving rate of the ratchet wheel together with the gear ratio of the 30 gears 24, 25 are such as to effect one revolution of the disc 27 when there has been unwound from the bobbin 10 an amount of yarn sufficient to complete one pirn, it being understood that the 35 number of traverses of the guide 13 is proportional to the length of yarn unwound from the bobbin, since the same amount of yarn is wound in each layer on the bobbin.

After one revolution of the disc 27, the projection 32 falls into the notch 28 to allow the lever 40 30 to rock and bring the downwardly depending wire 35 behind an abutment 36 on the usual traverse spindle 37 of the pirn winding mechanism. On the next rearward motion of the traverse spindle 37, the abutment 36 presses the wire 45 35 against the projecting member 38 carried by the arm 39 and causes the arm to rock about its pivot 40, thus withdrawing the latch 41 from engagement with a lever 42 secured to the rod 43 of the usual starting and stopping lever. In this 50 way, the starting and stopping lever rod is released to throw out a clutch by means of the usual mechanism inside the gear box 44, thus bringing winding to an end. The clutch and clutch operating mechanism are of the type em- 55

ployed in the well-known "Leesona" winding machine made by the Universal Winding Company of Boston, Mass. When the winding has stopped, the completed pирн is removed from 5 spindle 15.

On recommencement of the winding operation a new pирн tube is fitted on the spindle 15 and the traverse mechanism 46 is re-set at a point near the gear box end of the traverse spindle 37, i. e. at 10 the base of the new pирн tube, where winding of the yarn 12 recommences.

The starting rod 43 is then rotated by hand to the "on" position to re-engage the driving clutch in the gear box 44 with the winding spindle 15.

15 The rotation of the starting rod 43 brings the lever 42 again into position to be engaged by the latch 41, the arm 39 being re-set about its pivot to effect such engagement and to bring the projecting member 38 again into operative position.

20 To prevent tripping of the stop mechanism at the commencement of winding of the new pирн, i. e. before the projection 32 has ridden up the incline 29 of the notch 28 on to the periphery of the disc 27, a wire 45 carried by the traverse mechanism 46 interposes itself between the wire 35 and the abutment 36 when the traverse mechanism is re-set near the gear box 44. As winding proceeds the traverse mechanism gradually moves from the base towards the tip of the pирн 25 and carries with it the wire 45, the withdrawal of the wire 45 allowing the wire 35 to move to operative position behind the abutment 36 when again released by the disc 27. The presence of the wire 45 at the base of the pирн tube at the commencement 30 of the winding operation holds wire 35 to the right of the traverse spindle 37 and thus assists the projection 32 to mount the slowly moving incline 29.

What I claim and desire to secure by Letters 40 Patent is: —

1. Apparatus for effecting the unwinding of a predetermined amount of yarn from bobbins and like packages having a substantially constant amount of yarn in each layer, said apparatus comprising means for unwinding yarn from such a package, a guide free to move lengthwise of the package and adapted to be engaged and moved by the unwinding yarn, a member adapted to stop 45

the yarn-unwinding means, and means driven by the movable guide and adapted to operate the stop member after a predetermined number of movements of the guide lengthwise of the package. 5

2. Apparatus according to claim 1, comprising a ratchet wheel, pawl means on the movable guide adapted to engage and rotate said ratchet wheel, a notched disc in driving connection with the ratchet wheel, a projection on the stop-member adapted to engage the periphery of the notched disc, and means adapted to cause the projection to enter the notch during the rotation of the disc and allow the stop-member to operate. 10

3. Pирн-winding apparatus comprising a winding spindle, a member adapted to effect stoppage of the rotation of said spindle, yarn traversing means, an abutment on the traversing means, a support for a bobbin or like package having a substantially constant amount of yarn on each 20 layer, a guide free to move lengthwise of the package and adapted to be engaged and moved by yarn drawn from the package by the rotation of the pирн-winding spindle, a stop-member movable to a position behind the abutment on the traversing means, means controlled by the movable guide to move the stop-member behind the abutment after a predetermined number of movements of the guide lengthwise of the package, and means against which the stop-member 25 is pressed by the abutment to effect operation of the member effecting stopping of the pирн-winding spindle. 30

4. Pирн-winding apparatus according to claim 3, comprising a notched disc, driving means connecting the disc and the movable guide so as to effect rotation of the disc, a projection on the stop-member adapted to engage the periphery of the disc and means adapted to cause the projection to enter the notch during the rotation of the 40 disc and allow the stop-member to move behind the abutment on the traversing means. 35

5. Apparatus according to claim 3 comprising a member carried by the traversing means and positioned so as to prevent the stop-member passing behind the abutment at the commencement of the pирн-winding operation. 45
